DESIGN FOR AN AIR WASHER CASING OR SIMILAR ARTICLE

Alfred J. Dalton, Detroit, Mich., assignor to Industrial Sheet Metal Works, Inc., Detroit, Mich.

Application August 18, 1941, Serial No. 102,911

Term of patent 14 years

To all whom it may concern:

Be it known that I, Alfred J. Dalton, a citizen of the United States, residing at Detroit, in the county of Wayne and State of Michigan, have invented a new, original, and ornamental Design for an Air Washer Casing or Similar Article, of which the following is a specification, reference being had to the accompanying drawing, forming part thereof.

Figure 1 is a perspective view of an air washer casing showing my new design; and

Figure 2 is a front elevational view thereof.

The dominant features of my design reside in the portions shown in full lines.

I claim:

The ornamental design for an air washer casing or similar article, as shown and described.
